UNITED STATES PATENT OFFICE

110,136

DESIGN FOR A TEXTILE FABRIC

Theodore R. Upland, San Francisco, Calif., assignor to Gantner & Mattern Company, San Francisco, Calif., a corporation of California

Application November 8, 1937, Serial No. 72,692

Term of patent 3½ years

To all whom it may concern:

Be it known that I, Theodore R. Upland, a citizen of the United States, residing at the city and county of San Francisco, State of California, have invented a new, original, and ornamental Design for Textile Fabrics, of which the following is a specification; reference being had to the accompanying drawing, forming a part thereof.

In the drawing the figure is a plan view of the fabric, showing my design.

The design unit is indicated in heavier lines in the upper left-hand corner of the drawing by dot and dash lines, the same being repeated at regular intervals as indicated by the surrounding ones.

I claim:

The ornamental design for a textile fabric, as shown and described.

THEODORE R. UPLAND.
